UNITED STATES PATENT OFFICE.

HOWARD J. MURPHY, OF READING, MASSACHUSETTS, ASSIGNOR, BY MESNE ASSIGNMENTS, TO THE BASSICK MANUFACTURING COMPANY, OF CHICAGO, ILLINOIS, A CORPORATION OF DELAWARE.

LUBRICATING APPARATUS.

Application filed March 14, 1922. Serial No. 543,849.

This invention pertains to improvements in lubricating apparatus. It is among the objects of the invention to improve that form of lubricating apparatus wherein a lubricant-receiving element is adapted to be readily connected to and disconnected from a source of lubricant under pressure.

In the drawings, which show a preferred form of one embodiment of my invention:—
10 Figure 1 is a side elevation of a preferred form of lubricant-expelling device coupled to a lubricant-receiving element;

15 Fig. 2 is a longitudinal central section through the discharge end of the lubricant-expelling device illustrated in Fig. 1, showing the lubricant-receiving element in elevation;

20 Fig. 3 is a section on the line 3—3 of Fig. 2, showing the relative position of the parts prior to the coupling operation;

25 Fig. 4 is a section on the same line as Fig. 3, but showing the relative position of the parts pursuant to the coupling operation;

Fig. 5 includes an end and a side elevation 30 of a preferred form of coupling sleeve;

Fig. 6 shows a preferred form of connecting sleeve for use within the coupling sleeve;

Fig. 7 shows a preferred form of retainer ring for the connecting sleeve;

35 Fig. 8 includes an end and a side elevation of a preferred form of sealing part;

Fig. 9 shows a valve part; and

Fig. 10 is a view, partly in section, on the same line as Fig. 2 but showing some of the 40 cooperating parts in elevation and in the relative position occupied prior to the coupling operation.

Referring to the drawings, which show a preferred form of one embodiment of my 45 invention, I have shown lubricant-expelling means which may include a barrel 11 provided with a rear head 12, into which is threaded a stem 13 carrying the usual piston or plunger for expelling the grease from the barrel. At the discharge end of the barrel, I have shown a front head 14 carrying coupling and valve means for cooperation with the lubricant-receiving element 15, herein shown as a nipple provided with 50 lateral projections 16. The preferred form of coupling illustrated includes a coupling sleeve 17 carried within an outer part 18 of the head 14 and containing within it a con-

necting sleeve 19. The coupling sleeve 17 is apertured at 20 to receive the head of the 55 lubricant-receiving nipple and to provide flanges 21 to underlie the projections on said nipple when turned relative thereto. The connecting part 19 is mounted for turning movement within the coupling sleeve 17 and is apertured at 22 to receive and embrace 60 the sides of the projections on the nipple. The preferred form of coupling also presents a sealing part 24 reciprocable within the nozzle or coupling sleeve 17 by cooperating pin and inclined slot means, the pins 25 being preferably carried by the sealing part 24, as illustrated, and movable within inclined slots 26, 26 in the coupling sleeve. 65

In the preferred form of my invention 70 illustrated, the sealing part 24 is centrally apertured at 27 to permit passage of lubricant therethrough, being transversely slotted at 28 at its rear end and having thereagainst a valve part 29 (Figs. 2 and 9) having apertures adapted to be turned into registering or non-registering position relative to the slot 28. Relative turning movement between the sealing part 24 and the valve part 29 is effected by mechanism providing deferred 75 opening of the valve after the coupling is completed and insuring closure of the valve prior to the uncoupling operation. In the preferred form of my invention illustrated, this deferred action is produced by clutch 80 means which may take the form, as illustrated, of the clutch ball 30 of slightly greater diameter than the thickness of the adjacent portion of the coupling sleeve 17 and carried in an opening through said 85 coupling sleeve. Cooperating indentations are provided in the part 18 surrounding the coupling sleeve and in the sealing part 24 thereon. Until completion of the coupling operation, the ball clutch 30 occupies the 90 position shown in Fig. 3, partly within the surrounding wall 18 and partly within the coupling sleeve so that rotation between these parts cannot be effected. As the coupling sleeve and outer part are rotated 95 together as by turning the grease gun barrel in clockwise direction, the sealing part 24 cannot rotate therewith because a squared end 40 thereon is entered within the hole 22 of the connection part 19, the part 19 being 100 held against rotation by fitting the head of

the lubricant-receiving nipple secured to the part to be lubricated. Rotation of the coupling sleeve 17 relative to the sealing part 24 in a clockwise direction will move the sealing part 24 toward the lubricant-receiving end of the nipple 15 to press the sealing washer 41 thereagainst, this endwise movement being effected by the screws 25 cooperating with the inclined slots 26. During this movement, the depression 42 in the sealing part will come opposite the clutch ball 30, and the ball will pass therein to the position illustrated in Fig. 4, thereby permitting rotation of the outer wall 18 with the head 14 while permitting the coupling 17 to remain in fixed relation to the sealing part 24. The valve part 29 is secured to the outer wall 18, and, as this is turned relative to the sealing part 24, the cooperating ports therein will be brought into register with the slot 28 in the sealing part 24, thus opening the valve. The extent of this movement is limited by the screw 50 carried by the outer wall 18 and engaging a slot 51 in the coupling sleeve 17.

The connecting sleeve 19 is held in its forward position by the resilient ring 53 (Figs. 2 and 7), so that there is no opportunity for grit to get in between the end thereof and the interior faces of the flanges 21. Leakage around the valve part 29 and sealing part 24 is opposed by an apertured cup washer 54 secured to the valve part 29.

Assuming the nipple 15 to be entered in the nozzle prior to rotation thereof, the parts will occupy the relative position shown in Fig. 10. As the gun barrel is rotated to the right, it will turn with it the front head 14 and outer wall 18 of the nozzle. The coupling sleeve 17 will also turn with it, as it is held in fixed relation to the outer part 17 by the ball 30, occupying the interlocking position illustrated in Fig. 3. During this time, the sealing part 24 cannot turn relative to the nipple because held by the connecting sleeve 19. Therefore the sealing part 24 will be moved forward to the left, as viewed in Figs. 10 and 2, until the position shown in Fig. 2 is reached with considerable pressure of the sealing washer 41 against the head of the nipple 15. By this time the clutch ball 30 will reach the position shown in Fig. 4, permitting turning movement of the outer part 18 without corresponding movement of the coupling sleeve 17, and such turning movement will be effected by further turning of the barrel 11 until the ports in the valve part 29 come in register with the slot 28 in the sealing part 24, at which time the screw 50 will have reached the end of its slot 51 and the coupling and valve opening will have been completed.

Assuming now that the desired amount of lubricant has been expelled, the barrel 11

may be turned to the left. The first part of this movement cannot effect relative rotation between the coupling sleeve 17 and the sealing part 24 because the ball clutch 30 opposes any movement between them. Therefore, the outer wall 18 will turn relative to the sealing part 24 and bring the ports in the valve part 29 out of register with the slot 28 in the sealing part 24 until the screw 50 has reached the opposite end of the slot 51, at which time the valve will be entirely closed. By this time, the clutch ball 30 will have come opposite the recess in the outer wall 18 (as shown in Fig. 3) and further turning movement of the barrel in a counterclockwise direction, as viewed from its rear end, will cause the coupling sleeve 17 to turn so that the nipple may be withdrawn from the aperture 20, the sealing part 24 being retracted during this uncoupling movement to the position shown in Fig. 10, thus completing the cycle of operations. It will be noted that during the uncoupling operation, the sealing part 24 is drawn back against the pressure of the lubricant behind it, and that the valve part 29 reciprocates with the sealing part 24 during the coupling and uncoupling operations.

While I have shown and described a preferred form of one embodiment of my invention, it will be understood that changes involving omission, substitution, alteration and reversal of parts, and even changes in the mode of operation, may be made without departing from the scope of my invention, which is best defined in the following claims.

Claims:

1. Lubricating apparatus of the class described comprising, in combination, a coupling part for connection with and disconnection from a nipple, an aligned valve, and shiftable clutch means for locking some of the parts of said coupling against relative rotation to insure initial completion of the coupling operation, said clutch means thereafter shiftable to unlock the parts of said coupling to permit opening of said valve.

2. Lubricating apparatus of the class described, comprising in combination, a coupling part for connection with and disconnection from a lubricant-receiving nipple, said coupling including a nozzle sleeve, a sealing part, a valve part and shiftable clutch means, said clutch means operable to lock some of said parts during coupling to prevent operation of said valve and other of said parts to prevent uncoupling during valve opening and closing operation.

3. In lubricating apparatus of the class described, a lubricant compressor having a coupling connected to its discharge end, a valve for controlling flow of lubricant toward said coupling, said valve aligned with said coupling, and a shiftable clutch means

operatively interposed between said coupling and said valve, said clutch opening said valve after said coupling has been connected to a lubricant receiving part.

5. Lubricating apparatus of the class described including a coupling and a deferred operation valve controlling flow of lubricant toward said coupling, said valve and coupling operable by similar manipulative 10 movement, and clutch means between said coupling and valve, said clutch means including a ball and a plurality of ball receiving sockets co-operating to effect operation of said coupling before permitting operation 15 of said valve.

5. Lubricating apparatus of the class described including a coupling and a deferred operation valve controlling flow of lubricant toward said coupling, said valve and 20 coupling operable by similar progressive manipulative movement, and clutch means between said coupling and valve, said clutch means including a ball and a plurality of ball receiving sockets co-operating to effect 25 operation of said coupling before permitting operation of said valve.

6. Lubricating apparatus including a lubricant-expelling gun having a barrel containing lubricant and carrying a coupling 30 including a sleeve presenting portions to underlie lateral projections on a lubricant-receiving nipple when coupled to said nipple, said coupling also including a sealing part pressed tightly against the end of the nipple 35 during coupling operation, said sleeve rotatable with said barrel to effect coupling thereof to the nipple, and said barrel rotatable without rotation of said sleeve to effect opening and closing of a cooperating 40 valve after said sealing part has been pressed against said nipple.

7. Lubricating apparatus including a lubricant-expelling gun having a barrel containing lubricant and carrying a coupling 45 including a sleeve presenting portions to underlie lateral projections on a lubricant-receiving nipple when coupled to said nipple, said coupling also including a sealing part pressed unyieldingly against the end of the nipple 50 when coupled, said sleeve rotatable with the barrel to effect coupling thereof to said nipple, and said barrel rotatable without rotation of said sleeve after coupling is 55 completed to effect opening of a cooperating valve without axial movement of the barrel relative to said sleeve.

8. A lubricant-expelling gun rigidly and directly carrying a coupling including a sleeve presenting an opening at its exposed 60 end adapted to fit over projections on a cooperating lubricant-receiving part, said sleeve presenting adjacent said end overhanging portions for engagement beneath said projections, and means forcing said sleeve to turn with the body of said expelling 65

device during the coupling operation and permitting independent turning of said body to operate valve mechanism interposed between said body and said overhanging portions.

9. Lubricating apparatus including a lubricant-expelling gun directly carrying a coupling for engagement with a lubricant-receiving nipple and a rotary valve controlling discharge of lubricant, said expelling gun also presenting coordinating shiftable clutch means insuring proper sequence of operation of said coupling and of said valve by insuring, when coupling, operation of said coupling prior to opening of said valve, and by insuring, when uncoupling, closure of said valve prior to uncoupling, said coupling and valve being operable automatically in sequence by a single continuous movement of said gun.

10. Lubricating apparatus including a lubricant-expelling device presenting a nozzle providing means for engagement beneath projections provided on a lubricant-receiving nipple, a sealing part movable toward and from the nipple during coupling and uncoupling of said nozzle with the nipple and a sleeve engaging said nipple and said sealing part to oppose turning of said sealing part relative to the nipple during the coupling operation.

11. Lubricating apparatus including a lubricant-expelling device presenting a nozzle providing means for engagement beneath projections provided by a lubricant receiving nipple, a sealing part movable toward and from the nipple during coupling and uncoupling of said nozzle with the nipple and a sleeve engaging the nipple and said sealing part to oppose turning of said sealing part relative to the nipple during the coupling operation, said sleeve slidably engaging said sealing part.

12. Lubricating apparatus including a lubricant-expelling device presenting a nozzle providing means for engagement beneath projections provided by a lubricant-receiving nipple, a sealing part movable toward and from the nipple during coupling and uncoupling of said nozzle with the nipple and a sleeve engaging the nipple and said sealing part to oppose turning of said sealing part relative to the nipple during the coupling operation, said sleeve having a non-circular aperture extending completely therethrough and engaging laterally the nipple and the adjacent end of said sealing part.

13. Lubricating apparatus including a lubricant-expelling device presenting a nozzle providing means for engagement beneath projecting means provided by a lubricant receiving nipple, a sealing part movable toward and from the nipple during coupling and uncoupling of said nozzle with the nipple and a sleeve engaging the nipple and

said sealing part to oppose turning of said sealing part relative to the nipple during the coupling operation, said sleeve slidably engaging said sealing part and having a non-circular aperture therethrough of constant cross-section.

14. Lubricating apparatus of the class described including a coupling having an unyielding torque-pressed sealing element non-rotatable relative to a lubricant-receiving nipple, valve means, and coordinated clutch means controlling operation of said valve means and said coupling.

15. Lubricating apparatus of the class described including a coupling having an unyielding torque-pressed sealing element non-rotatable relative to a lubricant-receiving nipple, valve means, and coordinated clutch means controlling operation of said valve means and said coupling while permitting operation of said torque-pressed sealing element at all times when under torque in sealing direction.

16. Lubricating apparatus of the class described including a lubricant expelling device having a coupling adjacent its discharge end for engagement with a lubricant receiving nipple having lateral projections thereon, said coupling presenting a sealing part and a sleeve slidably engaging said sealing part and said lateral projections on said nipple to prevent relative rotation therebetween.

17. Lubricating apparatus comprising, in combination, a lubricant-expelling device having a coupling adjacent its discharge end for engagement with a lubricant-receiving nipple presenting lateral projections, said coupling presenting a sealing part and a sleeve slidably engaging said sealing part and the lateral projections on the nipple to oppose relative turning therebetween, and resilient means holding said sleeve in forward position toward the discharge end of said coupling.

18. Lubricating apparatus of the class described including coupling means for engagement with a lubricant-receiving nipple and presenting a sealing part pressed tightly against the nipple when coupling is effected, valve means, and coordinated clutch means including a shiftable part for controlling operation of said valve means and said coupling.

19. Lubricating apparatus of the class described including a lubricant delivering compressor having at its discharge end a quick detachable coupling for connection by movement of said compressor relative to a lubricant receiving element, said coupling providing a valve, and clutch means positively interlocked to oppose opening of said valve until completion of the coupling operation.

20. Lubricating apparatus including a

lubricant delivering compressor having at its discharge end a coupling for connection by movement of said compressor relative to a lubricant receiving element, said coupling providing a valve, and clutch means positively interlocked to oppose opening of said valve until completion of the coupling operation, said clutch means shiftable upon completion of the coupling operation, thereby to positively prevent uncoupling of said delivering compressor from said receiving element until completion of the valve closing operation.

21. Lubricating apparatus comprising a lubricant expelling gun carrying a coupling part having an axial opening to receive a polygonal portion on a lubricant receiving nipple and chambered interiorly to present flanges to underlie the projections presented by the polygonal portion when the latter is entered therein and turned relative thereto, a co-operating sealing part, a valve, a valve operating means and clutch means precluding opening of said valve until the polygonal flanges and sealing part are turned relative to one another a predetermined distance and until the coupling and sealing operation are both completed.

22. Lubricating apparatus of the class described comprising a lubricant expelling compressor having a quick detachable coupling means and a valve means connected to its discharge end, and correlated but non-synchronously operated clutch mechanism interconnecting said means, said clutch mechanism including apparatus for first engaging one of said means and thereafter engaging the other of said means.

23. Lubricating apparatus including a lubricant delivering compressor having a coupling and sealing mechanism for connection with and disconnection from a lubricant receiving nipple, a valve, and coordinated locking means carried by said coupling and sealing mechanism for preventing relative rotation between the sealing part and coupling part during valve opening or closing operation.

24. Lubricating apparatus including a lubricant delivering compressor having a coupling and sealing mechanism for connection with and disconnection from a lubricant receiving nipple, a valve, and coordinated clutch means carried by said coupling and sealing mechanism for preventing valve opening operation during sealing and coupling operation and unsealing and uncoupling operation.

25. Lubricating apparatus including a lubricant delivering compressor presenting a coupling part for connection with and disconnection from beneath projections on a lubricant receiving nipple, a sealing part, a third part mounted for turning movement relative to said coupling part and said seal-

ing part, and valve means the entire movement of which is actuated by relative turning movement between said coupling part and said third part subsequent to completion of 5 the coupling and sealing operation.

26. Lubricating apparatus including a lubricant delivering compressor having a nozzle sleeve, a coupling sleeve, a sealing part, a valve, and clutch means operatively 10 interposed between said nozzle sleeve, cou-

pling sleeve and sealing part initially to lock two of said parts against relative rotation during engagement and disengagement with a lubricant receiving nipple and thereafter to lock the third of said parts to one of the 15 other of said parts to effect valve opening or closing.

In testimony whereof, I have signed my name to this specification.

HOWARD J. MURPHY.
